UNITED STATES PATENT OFFICE.

CHESTER R. PIEPER, OF LA CROSSE, WISCONSIN.

EARTH-ANCHOR.

1,123,368.

Specification of Letters Patent.

Patented Jan. 5, 1915.

Application filed August 7, 1913. Serial No. 733,543.

To all whom it may concern:

Be it known that I, CHESTER R. PIEPER, citizen of the United States, residing at La Crosse, in the county of La Crosse and 5 State of Wisconsin, have invented a certain new and useful Improvements in Earth Anchors, of which the following is a full, clear, concise, and exact description, reference being had to the accompanying drawings, forming a part of this specification.

10 My invention relates to earth anchors and has a number of objects and advantages in view.

The invention has for one of its objects 15 the provision of a construction including an anchor rod and anchor blades in association therewith, between which rods and blades there need be no rotation in order to spread the blades into the earth. In 20 practicing this feature of the invention the anchor rod carries a spreader at its lower end which coöperates with neither faces of the blades when the tops of the blades are impinged upon by a suitable tamping tool. 25 In the preferred embodiment of the invention the anchor blades are articulated at the rod, each blade being provided with a pair of trunnion extensions for this purpose, the anchor rod so passing through spacings afforded between these trunnion extensions as 30 to maintain the articulation.

Interlocking means are provided for maintaining the blades in their spread apart relation, such interlocking means preferably 35 including, as one portion thereof, a spreader carried upon the lower end of the anchor rod and, as another portion, notched or recessed parts formed in the nether surfaces of the anchor blades, the desired interlocking engagement being secured when the blades have been sufficiently spread apart 40 for the purpose of securing the anchor in position, a return of the blades to their folded relation thereafter being prevented 45 by the interlocking action. This feature of the invention is not to be limited to the construction above described nor to the preferred form of earth anchors in which there is no necessary relative rotary motion between the anchor rod and anchor blades.

50 My invention has other characteristics and will be explained fully by reference to the accompanying drawing in which—

Figure 1 is a side view of the earth anchor 55 of my invention, the position of the blades before they are spaced apart being shown in

full lines and their position after being spread apart being shown in dotted lines; Fig. 2 is a view of the structure as it appears in full lines in Fig. 1, but taken at right angles to the direction in which Fig. 1 is taken; Fig. 3 is a sectional view on line 3—3 of Fig. 1 of that portion of the structure where the blades are articulated together; Fig. 4 is a plan view of the central portion of the blade structure with the anchoring stem in section; and Fig. 5 is a perspective view illustrating a preferred structural characteristic where the blades of the anchor are articulated.

Like parts are indicated by similar characters of reference throughout the different figures.

The anchor rod *a* is preferably in threaded connection with the spreader *b* shown in the form of a flat disk. The earth penetrating blades *c* are symmetrically formed. An inwardly extending trunnion extension *d* on each blade carries an insetting trunnion pin *e* which passes through a trunnion extension *d'* on the other blade, the trunnion extensions on each blade being interleaved or alternating with the trunnion extensions on the other. Sufficient spacing intervenes between the two inner trunnion extensions *d'* (on different blades) to permit the anchor rod *a* to pass between them, though such spacing is sufficiently narrow to enable the anchor rod to keep the extensions *d'* on the pins *e*. Thus the anchor rod acts as a holding device to maintain the articulation of the blades whereby any special device for this purpose need not be employed. The blades and the lower end of the anchor rod are inserted in a prepared hole in the earth in the collapsed position indicated in full lines in Figs. 1 and 2 whereafter a bifurcated tamping tool is applied to the top portions of the trunnion extensions to force the blades to ride over the spreader *b* whereby 95 said blades are projected laterally (as indicated by dotted lines in the power part of Fig. 1) into the surrounding earth. The spreader *b* finally enters notches *f* provided in the opposing or bottom faces of the blades 100 *c* to lock the blades apart.

Each blade may have an insetting extension *g* spread apart at recess *h* from the trunnion extension *d* carried by the blade having such extension, this recess receiving 110 the trunnion extension *d'* of the companion blade whereby articulation of the blades

may be maintained independently of the anchor rod. Each trunnion extension is reduced in diameter at i so that when the blades are sufficiently folded back from the position illustrated in Fig. 1 the blades may be separated.

While I have herein shown and particularly described the preferred embodiment of my invention I do not wish to be limited to 10 the precise details of construction shown as changes may readily be made without departing from the spirit of my invention.

Having thus described my invention I claim as new and desire to secure by Letters 15 Patent the following:—

1. An earth anchor including a pair of anchor blades articulated at adjacent inner ends to enable them to be spread apart from collapsed position; an anchor rod passing 20 freely through spacing provided between the anchor blades where articulated to permit tamping of the blades; and a spreader provided at the lower end of the anchor rod, the nether faces of the anchor blades being 25 shaped to coöperate with the spreader whereby the blades will be laterally projected into the earth when the articulated portions of the blades are tamped, there being notches f in opposing or bottom faces of the blades 30 which are engaged by the spreader when the blades are spread apart to hold the blades apart.

2. An earth anchor including a pair of anchor blades articulated at adjacent inner ends where the blades are provided each 35 with a pair of trunnion extensions, the trunnion extensions of each blade being inter-

leaved with the trunnion extensions of the other, both blades having each a recess h for receiving the two inner trunnion extensions carried by the blades to maintain the 40 articulation of the blades.

3. An earth anchor including a pair of anchor blades articulated at adjacent inner ends where the blades are provided each 45 with a pair of trunnion extensions, the trunnion extensions of each blade being interleaved with the trunnion extensions of the other; an anchor rod element passing through spacing provided between the two 50 inner trunnion extensions that project from the two blades, said anchor rod element and spacing being so proportioned as to enable the anchor rod element to maintain the articulation between the anchor blades; and 55 means for maintaining such articulation independently of the anchor rod when the blades are spread apart.

4. An earth anchor including a pair of anchor blades articulated at adjacent inner 60 ends where the blades are provided each with a pair of trunnion extensions, the trunnion extensions of each blade being interleaved with the trunnion extensions of the other; and means interposed between the 65 two inner trunnion extensions for maintaining the articulation between the blades.

In witness whereof, I hereunto subscribe my name this fourth day of August A. D., 1913.

CHESTER R. PIEPER.
